UNITED STATES PATENT OFFICE.

GEBHARD JAEGER, OF COLUMBUS, OHIO.

CONCRETE-DISTRIBUTING APPARATUS.

1,248,662.

Specification of Letters Patent.

Patented Dec. 4, 1917.

Application filed January 24, 1916. Serial No. 73,830.

To all whom it may concern:

Be it known that I, GEBHARD JAEGER, a citizen of the United States, residing at Columbus, in the county of Franklin and State of Ohio, have invented a certain new and useful Improvement in Concrete-Distributing Apparatus, of which the following is a specification.

The invention relates more particularly to tracks for use in connection with concrete distributing apparatus.

The object of the present invention is to provide an improved construction inclined track which is simple and easy to erect and which may be manufactured at small cost so as to be within the reach of the contractor of limited means. Another object is to provide a track which may be easily taken apart and compacted for storage or transportation.

This invention is embodied in the construction and combination of parts herein shown and described and then pointed out in the claims.

In the accompanying drawings—

Figure 1 is a general view in side elevation showing an apparatus for the special purpose stated according to my invention.

Fig. 2 is a detail on a larger scale showing the joined sections of the inclined way or track.

Fig. 3 is a plan view of the same.

Fig. 4 is a detail in side view showing the construction of the hooking or lower end of the track section.

Fig. 5 is a similar detail showing the other or upper end of a section like that referred to in Fig. 4.

Fig. 6 is a detail in sectional view on the line $x-x$ Fig. 2 looking up.

Fig. 7 is a detail in side view of the upper portion of one of the track supporting legs.

Fig. 8 shows how the hook end of a track section is positioned with reference to the non-hook end of another section to effect the connection or disconnection of the sections.

In the views 10 designates an intermediate track section which is composed of two bars each preferably of rolled steel of E -form in cross section. Each bar of such section has at one end a hook 11 and a pair of tongues 12 to embrace an alined bar or track. The other end of each of the bars of the section is provided with an eye 13. A rod 14 is passed through and suitably secured in said eyes. To join one section to another the hooks 11 are placed over a rod 14 of

such other section while in the relative or angular position shown in Fig. 8 and then the section to be hooked is turned up until it alines with the other section to form a continuous track upon which the wheels of a truck, as hereinafter described, can run. When the sections are thus joined and alined one cannot be raised with reference to the other and can only be separated by bringing the one to be separated to the angular relation first described. The first or lowest track section rests upon the ground at the incline desired for the whole track, its upper end being supported by a leg frame 15, as seen in Fig. 1, having the upper end of its side pieces notched out as seen at 15^a in Fig. 7 to engage the cross rod 14. As many of these track sections as seen at 16 and 17 are added to the first described section and supported at their junctions as seen at 16 and 17 to secure the desired extension and elevation of the track. The upper end of the track is provided with a hopper 18.

Beyond the high point of the track there is provided a triangular frame 19 pivoted to swing in a horizontal direction on a column 20 supported on a base 21 and held at its upper end by a horizontal rod 22 resting on or secured to the cross rods of the legs. Supported upon the triangular swinging frame is a spout composed of two sections 23 and 24. The upper end of the lower spout section 24 is supported upon a hinged fork 25 pivoted in the free end of the triangular frame so as to be capable of swinging horizontally and vertically. The spout sections 23 and 24 are therefore movable horizontally with reference to each other and to the discharge of the hopper 18, but the upper end of the spout section 23 lies constantly under the hopper. The hopper therefore discharges into the spout sections and the discharge of the lower spout section can be directed to the point where the concrete is to be poured, as for example, along the straight lines of the four sides of the place where the foundation of an ordinary house is to be built.

26 designates generally a concrete mixing machine of a construction now in common use except that for the purposes of the present invention it contains a motor driven windlass 26^a. 27 designates a truck to travel on the inclined track, said truck containing a tilttable, but normally balanced bucket 28. The truck is connected with a cord 29 run-

ning around a suitable pulley (not shown) to wind on the windlass so that the truck with its bucket can be drawn up on the track and lowered as desired. The bucket is provided with a rigid arm 30 which when the truck is drawn to the top of the inclined track strikes a rigid lug 31 on the track causing the bucket to turn and discharge its contents into the hopper 18. In its lowered position the bucket receives the mixed contents from the mixing tank 32 which is tiltable for the purpose.

With this construction one batch of concrete can be mixed in the mixer while a bucket is being elevated and discharged so that the operation is made continuous and speedy.

What I claim is:

1. An inclined track including rail sec-

tions and means for detachably connecting 20 said sections consisting of hooks on one end of the section, means on the other end of the section for receiving similar hooks on another section, and means for supporting the connected sections in inclined position 25 consisting of a frame adapted to detachably engage the hook receiving means.

2. An inclined track including rail sections and means for detachably connecting said sections consisting of hooks on one end 30 of the section, means on the other end of the section for receiving similar hooks on another section, and means for supporting the connected sections in inclined position consisting of a movable frame adapted to engage one of the sections near its junction with another section.

GEBHARD JAEGER.
